UNITED STATES PATENT OFFICE

104,232

DESIGN FOR A COMBINED GLOBE AND PANEL FOR A LIGHTING FIXTURE

Albert L. Arenberg, Highland Park, Ill., assignor
to Patent License Corporation, Chicago, Ill., a
corporation of Illinois

Application November 16, 1936, Serial No. 65,935

Term of patent 14 years

To all whom it may concern:

Be it known that I, Albert L. Arenberg, a citizen
of the United States, residing at Highland Park,
in the county of Lake and State of Illinois, have
invented a new, original, and ornamental Design
for a Combined Globe and Panel for a Lighting
Fixture, of which the following is a specification,
reference being had to the accompanying drawing,
forming a part thereof.

In the drawing:

Fig. 1 is a perspective view of the combined

globe and panel, showing my new design;

Fig. 2 is a face view; and

Fig. 3 is an end view.

The surfaces of the panel which are shown
stippled in the drawing are of a character to
diffuse the light.

I claim:

The ornamental design for a combined globe
and panel for a lighting fixture, substantially as
shown and described.

ALBERT L. ARENBERG.
